CLAIM

The ornamental design for a container, substantially as shown and described.

DESCRIPTION

FIG. 1 is a perspective view of a container showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is a perspective view thereof, with the first and secondary lids in the open position;

FIG. 9 is a front view thereof;

FIG. 10 is a rear view thereof;

FIG. 11 is a top plan view thereof;

FIG. 12 is a bottom plan view thereof;

FIG. 13 is a left side view thereof;

FIG. 14 is a right side view thereof;

FIG. 15 is a perspective view thereof, with the first lid in the open position and secondary lid in the closed position showing the utensil;

FIG. 16 is a front view thereof;

FIG. 17 is a rear view thereof;

FIG. 18 is a top plan view thereof;

FIG. 19 is a bottom plan view thereof;

FIG. 20 is a left side view thereof; and,

FIG. 21 is a right side view thereof.

In the drawings, the broken lines showing portions of a container depict environment and form no part of the claim.

1 Claim, 21 Drawing Sheets
